CLAIM

The ornamental design for a bed for animals, as shown and described.

DESCRIPTION

FIG. 1 is a front, right and top perspective view of a bed for animals, showing my new design;

FIG. 2 is a front, left and bottom perspective view thereof;
FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view of the bed for animals of FIG. 1, shown in a second configuration with the post attached to the bed;

FIG. 10 is a front, left and bottom perspective view thereof; and,

FIG. 11 is a perspective view thereof, shown in a third configuration with the arm and the bed shown separately to reveal aspects of the design that would not be apparent in other views.

The broken lines shown in the drawings illustrate portions of the bed for animals that form no part of the claimed design.
